BASE PLATE FOR FROGS AND CROSSINGS

Theodore W. Stedman, New York, N. Y., assignor
to The Firestone Tire & Rubber Company,
Akron, Ohio, a corporation of Ohio

Application August 26, 1943, Serial No. 500,145

1 Claim. (Cl. 238—283)

1

This invention relates to base plates for the frogs and crossings of railroad trackways, and more especially it relates to base plates of the character mentioned adapted resiliently to support frogs and crossings in their entirety.

Frogs and other special types of railway track construction, such as crossings, are subject to especially hard wear, yet require to be extremely durable since they must have a high factor of safety because of the hazards involved in case of failure. In order to improve the wearing qualities of frogs and crossings, the elements thereof that are subject to greatest wear are made of special hardened steels, which greatly adds to the cost. The wear upon frogs and crossings is caused by the impact load of heavy locomotives and other rolling stock moving thereover, and it is the common practice of most railway companies to mount frogs and crossings upon heavy steel plates of approximately $\frac{3}{4}$ inch thickness for the purpose of equalizing and distributing the impact load.

To compensate, in part at least, for the rigidity of the structural units, efforts have been made to cushion the units and thus reduce as much as possible the wear and tear upon the expensive special elements of the units. Unlike ordinary tangent track, a frog or crossing requires to be limited to a bare tolerance of movement, and such movement that does take place has to be definitely controlled. To impart a vertical cushioning effect to relieve the stresses arising from impact, rubber pads have been interposed between the respective ties and the steel base plate of a unit. In other cases, rubber pads coextensive in area with the metal base plates have been interposed between the latter and the ties. Neither of these expedients has been entirely satisfactory since the only cushioning contact has been immediately above the individual ties.

The chief objects of the invention are to provide an improved base plate for frogs and crossing units that will cushion the same; that will maintain the original unified rigidity of the units; and that will enable the units to deflect uniformly with an equal distribution of the load throughout their structures. More specifically the invention aims to reduce the maintenance expenses of frogs and crossings, and the ties on which they are supported. Other objects will be manifest as the description proceeds.

Of the accompanying drawing:

Fig. 1 is a plan view of a railway frog, a base plate embodying the invention operatively associated therewith, and ties upon which the base plate is mounted and secured;

Fig. 2 is a plan view, on a larger scale, of the improved base plate;

Fig. 3 is an edge view of the improved base

plate, a part thereof being sectioned on line 3—3 of Fig. 2; and Fig. 4 is a section, on a larger scale, on the line 4—4 of Fig. 1.

2 Referring now to Fig. 1 of the drawing, there is shown an improved base plate that is designated as a whole by the numeral 10, said base plate being secured to railroad ties 11 by lag screws 12, 12, and supporting on its upper face a rail frog 13. The latter is secured to the base plate 10 by a plurality of cleats 14 that are removably attached to the base plate by bolts 15. The area and proportions of the base plate will vary according to the particular frog or crossing with which it is designed for use, said frogs comprising several different types.

As is clearly shown in Fig. 3, the base plate 10 is a composite, laminated structure composed of resilient elements and rigid elements. More specifically, there are three resilient elements and two rigid elements, each of the latter having a resilient element on each side thereof. The rigid elements, designated 17, 17, are of substantially identical structure, each consisting of a steel plate of a quality known as "medium carbon." These plates may be relatively thin as compared to the thickness of all-metal base plates heretofore employed, a thickness of $\frac{3}{16}$ inch being found sufficient in most cases. Interposed between the metal plates 17 is a layer 18 of resilient rubber composition of relatively high modulus, said layer being permanently bonded to the confronting faces of the metal plates 17 by vulcanization. The layer 18 is relatively soft (about 35 durometer hardness) and in the illustrated embodiment of the invention is of $\frac{1}{4}$ inch thickness.

Vulcanized to the opposite face of one of the metal plates 17 is a layer 20 of rubber composition of medium modulus. The layer 20 is about 50 durometer hardness and thus is not as soft as the intermediate rubber layer 18. Also it is thinner than the latter, being but $\frac{1}{8}$ inch thickness. The layer 20 constitutes the bottom layer of the base plate 10 when the plate is in use as shown in Fig. 1, said layer 20 then resting in contact with the ties 11. Vulcanized to the opposite face of the other metal plate 17 is a layer 21 of a synthetic rubber-like material which may be the material known as neoprene (a polychloroprene). The layer 21, which constitutes the top facing of the composite base plate, is of the same thickness as the bottom layer 20. It is of high modulus (about 73 durometer hardness) and therefore is stiffer than the other resilient elements of the structure.

55 In the manufacture of the improved base plate a plurality of determinately arranged apertures 24, 24 are formed therein, said apertures being square in plan, of larger area in the bottom face of the plate than in the top face thereof, and of stepped formation between the said top and bot-

tom faces. The apertures 24 constitute seats or sockets for metal inserts 25 that have exterior lateral faces shaped complementary to the shape of said apertures. Each insert 25 has an axial aperture 26 therein, which aperture is tapered toward the smaller end of the insert, said aperture being spare at the small end of the insert and circular at the larger end thereof. The bolts 15 that secure the cleats 14 to the base plate 10 have tapered heads that are receivable in the tapered apertures in the inserts 25. The inserts 25 are mounted in the apertures 24 of the base plate and bonded thereto by vulcanization at the time the base plate is vulcanized.

The base plate 10 also is provided with a plurality of circular apertures 28, 28 for receiving the lag screws 12 by which the base plate is secured to the ties 11. The apertures 28 are formed by drilling, and this preferably is done by the customer who will drill the same in accordance with the spacing of the ties 11, such spacing differing in various frog and crossing installations. The arrangement is such that the plates 17 do not move in their own planes relatively of each other or relatively of the ties or the frog or crossing, any movement of said plates being very slight, and normal to their planes. Furthermore, the composite base plate supports the entire frog or crossing structure, thus substantially preventing relative movement between the various elements of said structure, equalizing and distributing impact load thereon, and obviating wear and shearing strains. The arrangement also obviates the imposition of shearing strains on the non-metallic components of the base plate.

Although only neoprene is mentioned as the composition of the top facing 21 of the base plate, it is not intended that the invention be limited to this particular material, but that other synthetic rubber-like compositions having some or all of the physical and chemical characteristics of neoprene may be substituted in lieu thereof. Among such characteristics may be mentioned the ability to resist the deteriorating effect of oil and grease, good aging qualities upon exposure to the elements, and resistance to the charring effect of hot cinders. Among synthetic compositions that may be substituted for neoprene are the plastics known by the trade name of "Buna," for example, "Buna S" (a copolymer of butadiene and styrene). Since the composition of the top layer 21 is relatively stiff, it does not readily flow and is not excessively deformed and displaced by the weight of the frog 13 that rests upon local regions thereof.

The soft, relatively thick intermediate resilient layer 18 absorbs most of the deflection of the upper plate 17 when the latter is subjected to strain and jolts arising from the impact of car wheels passing over the frog 13. Thus but little of such strain is imparted to the lower plate 17, and such strain that is imparted thereto is distributed uniformly thereover. It is for this reason that the combined thickness of the two metal plates 17 is less than the thickness of the single metal plates heretofore employed, with resulting economy of material. Moreover there is but little impact translated to the ties 11, with the result that much wear on the latter is avoided. This is especially advantageous in street railway trackage where the ties are embedded in the con-

crete base of a pavement, and replacement of worn ties is difficult and time-consuming. The bottom resilient layer 20 of rubber composition prevents friction of the metal of the base plate 10 upon the ties and contributes to the prevention of wear upon the latter. Since the composition of this layer is of medium stiffness, it is not extensively deformed or displaced by local contact with the ties 11.

The invention provides an improved base plate that reduces wear on frogs, crossings, and ties of railway trackage, that conserves metal, that reduces noise, and which achieves the other advantages set out in the foregoing statement of objects.

Modification may be resorted to without departing from the spirit of the invention, or the scope thereof as defined by the appended claim, and the various dimensions set forth and the specific durometer hardness data are not employed in a limiting sense, but only as illustrative examples of the characteristics of one embodiment of the invention.

What is claimed is:

1. In a base plate of the character described, the combination of a pair of metal plates disposed one over the other in parallel relation, layers of resilient material coextensive with said plates disposed between them and on the top and bottom faces of the composite structure, said material being bonded to said plates, and metal inserts within and extending through the composite structure, each of said inserts being formed with an axial bore adapted to receive the head of a bolt by which a frog or crossing is secured to the base plate, said inserts being polygonal in transverse section and received within respective apertures of complementary shape in the base plate so as to be restrained against rotary movement relatively of the base plate when the bolts are tightened, each of said inserts being larger exteriorly at its lower end than at its top, and having its respective sides of stepped formation, thus providing surfaces that are parallel to the axis of the insert, thereby enabling the metal plates to have limited movement relatively of each other and of the inserts in a direction normal to their planes, yet restraining such relative movement of the plates in the direction parallel to their planes.
